Geo. Chamberlin
By Attorney J. D. Woodruff, Jr.

United States Patent Office.

GEORGE CHAMBERLIN, OF OLEAN, NEW YORK.

Letters Patent No. 65,724, dated June 11, 1867.

IMPROVEMENT IN STUMP-EXTRACTOR.

The Schedule referred to in these Letters Patent and making part of the same.

TO ALL WHOM IT MAY CONCERN:

Be it known that I, GEORGE CHAMBERLIN, of Olean, Cattaraugus county, in the State of New York, have invented certain new and useful Improvements in Stump-Pullers; and the following is a full, clear, and exact description of the same, reference being had to the accompanying drawings, making a part of this specification, in which—

Figure 1 represents a vertical section of the entire apparatus or machine.

Figure 2 shows a detached view of the cap-socket and rotating screw-nut.

Figure 3 is a plan or top view of the same.

The object of my invention is to facilitate the clearing of land by pulling the stamps with a most convenient, portable, and efficient apparatus, that will regulate itself to the line of draught on which the greatest strain comes, so as always to work easily without cramping, bending, or straining the screw or rotating-nut, as the power is being applied to the lever for operating it.

My invention consists in the arrangement of a tripod supporting a metal flanged cap or head, in the centre of which is a concave socket and a semispherical or convex washer for a rotating-nut to rest on, in combination with a double-threaded hollow metal screw, the same being provided with an internal rod to give strength and stability to the screw above the nut; also in providing an additional centre screw-rod with clutch-hooks, swivel, and pin, or hand-wheel, to take up the slack in the chain after hitching to the stump; also in the manner of attaching the lever or levers to the rotating-nut, they resting on the ledge of the cap or head, which supports the lever or sweep at a uniform distance from the ground, whether it be on an incline or on a level.

To enable others skilled in the art to make and use my invention, I will describe it in detail, referring to the drawings and to the letters marked thereon.

I make the derrick of square timbers, of any desired size or height, in the form of a tripod, two of them, A A, having trundle rollers a a in the bottom, the third one, B, having a foot, b, with a ball-and-socket joint, b', the top of each being bolted into the metal flanged head C in sockets c c c, cast for them, they being supported apart and at suitable distances by the brace-rods d d d. In the centre of the cap or head C is cast a semi-spherical concave socket, e, into which is fitted a half of a ball washer, E, with a hole through it to allow the double-threaded screw D to move freely. The rotating-nut F being of considerable length stands vertically, resting on the ball washer E; the main screw D being held from turning round when the grappling-chains are hitched to the hooks f f. On about the centre of the rotating-nut F are trunnions g g, to which the lever or sweep G is fastened, it having a support in an inclined position on the rim of the cap or head C, so as to keep the lower end at about the same distance from the ground when carried round to operate. I make the double-threaded screw D of cast iron, and cast the screw-threads on, as well as the rotating box or nut F, being cast in the same manner; and in order that the cast-iron screw D may have the greater strength, and be supported from the top, I cast it on a wrought-iron rod, h, or make it hollow and put in a wrought shaft with a screw and nut, i, to tighten down upon it at the top. In the bottom of the screw D I fit another screw, H, of wrought iron, which extends down and has a double hook, j j, working on a swivel, so that the screw H can be turned by the hand-wheel k in the bottom of the large screw D, and take up all of the slack in the chains which connect the grapples on the stump with the hooks f f of the machine.

Thus it will be seen that my invention differs from others in that there will be no side strain on the screws or the rotating screw-box, the ball-socket allowing it to conform to the line of draught in any position it may stand, the stump being within the tripod; and also there is much time saved in taking up the slack and tightening up the chains by the independent screw being operated by hand; and another very great advantage is that the lever or sweep that operates to pull the stump is so connected to the rotating-nut or screw-box, and then having a firm support on the cap or head; that it will not materially change its relative position or height from the ground, although the screw may lean or be carried considerably to one side of its bearing. The main screw and box that it is fitted into being cast and secured for strength in the manner above described, it will be seen that a cheap, durable, and most efficient stump-puller can be supplied.

Having thus fully described my invention, what I claim as new, and desire to secure by Letters Patent, is—

1. The metal flange cap or head, as constructed, having a concave socket into which is fitted a convex

washer to reduce the friction, and allow changing the position of the line of draught on the screw, in the manner and for the purposes herein described.

2. I claim the flange-cap C and socket concave washer E, in combination with the rotating screw-box or nut F and lever-sweep K, substantially as and for the purposes set forth.

3. I claim the construction of the cast-iron double-threaded screw, with its wrought-iron central supporting rod, to give strength and durability, as described.

4. I claim the screw-rod H, hand-wheel k, and double-hooked swivel j j, in combination with the main screw D for taking up the slack in hitching, as specified.

5. I claim supporting the lever-sweep G on the rim of the flange-cap C, so that it will operate substantially as and for the purposes herein set forth.
